Attorneys

UNITED STATES PATENT OFFICE

GEORGE H. DAUBNER, OF HARTFORD, WISCONSIN, ASSIGNOR TO YELLOW TRUCK & COACH MANUFACTURING COMPANY, OF PONTIAC, MICHIGAN, A CORPORATION OF MAINE

CRANK-CASE-VENTILATING SYSTEM

Application filed February 6, 1929. Serial No. 337,926.

The object of this invention being indicated by its title, and the usual considerations which occasion ventilating of crankcases being well known, the present invention may be understood to relate more particularly to novel and stationary ventilating means, adapted to be secured to the crankcase of an engine,—such as an engine which is provided with an oil-feed pipe and also with a breather pipe, or with equivalent pipes respectively suitable to the introduction and withdrawal of air.

The engine whose crankcase is to be ventilated being assumed incidentally to drive a usual radiator cooling fan, preferred embodiments of this invention may comprise parts so shaped and combined as to render any relative advance of air past said crankcase effective in producing opposite pressure differentials, respectively and below atmospheric, in the mentioned pipes.

It is an object of this invention to provide a novel breather can, which may be connected with an opening near the rear end of the crankcase, with air-feeding means,—preferably including an excess-pressure pipe connecting tangentially therewith. Air conditioning means may be provided within or associated with said can, to purify air advancing inwardly therethrough from a forwardly facing funnel, or the like; and, Walter S. Cochrane having disclosed and claimed (in his Patent No. 1,713,262, dated May 14, 1929) means rendering the delivery of a blast of air into a forwardly-facing funnel (as may be done by means such as radiator cooling fan, disposed in front thereof) effective to withdraw air through an oil-feed pipe, it is an object of the present invention, preferably using a special funnel provided with a plurality of exits, to provide a combination in which the mentioned breather-can organization and features of the mentioned Cochrane invention are conjointly employed.

Other objects of this invention may be best appreciated by the following description of an illustrative embodiment thereof, taken in connection with the appended claims and the accompanying drawings.

In the drawings:

Figure 1 is a front elevational view, with parts broken away.

Figure 2 is a side elevational view, taken substantially as indicated by the arrow 2 of Figure 1, with parts differently broken away. 55

Figure 3 is a top plan view, taken substantially as indicated by the arrow 3 Figure 2, but with parts differently broken away.

As to the details of that specific embodiment of the present invention which has been chosen for the purpose of illustration, an engine, partially shown at 10, and its crankcase 11, radiator 12, and a fan 13, driven by said engine, may be of any usual or preferred type; and said crankcase is shown as provided, near its rear end, with an air inlet opening 14. This inlet opening may advantageously be spaced at a considerable longitudinal distance from an additional or outlet opening 15; and the present invention should be understood to relate more particularly to novel means justifying reference to a forwardly-opening pipe 16, shown as inwardly connected with the former opening, as an excess-pressure pipe,—the means employed to create a positive pressure at the opening 14 being preferably so combined with some suitable means for withdrawal of air through the opening 15 as to justify designation of pipe 17, connected with the last-mentioned opening, as a reduced-pressure pipe,—the combined effect of the pressure differentials referred to being an improved circulation of air through the crankcase 11, or its equivalent. 75

The mentioned patent of Cochrane suggests the equipment of an oil-feed pipe 18 (which may be integral with the reduced-pressure pipe 17 and may include an interior baffle 19, defining an air-exit throat 20, which is shown as extending to an annular passage element 21) with an aspirating unit,—the latter preferably including a suitable funnel element and an inner pipe 23, adapted to cooperate with the mentioned annular element to produce a Venturi effect. A combined outflow pipe 24 may be carried, in a known manner, to a carburetor, not shown; or it may be so terminated as to produce an additional suction effect, as suggested in Figure 1. 100

The novel forwardly-facing funnel 25, with which the pipe 23 is shown as communicating, may receive and feed into pipe 23 a suitable blast of air (whether or not the latter is driven past the mentioned radiator and/or engine crankcase by means such as the fan 13) and, to obviate a duplication of funnels, the funnel 25 may serve also in feeding air into the forward and open end of the excess-pressure pipe 16 or its equivalent. For this purpose, the funnel 25 is shown as provided with a plurality of blast exit openings 25', 25'', communicating respectively with pipes 23 and 16,—the lower of these being shown as the larger; and, in order to produce an air-whirling and/or other conditioning effect within a breather can 28, in case such a can is interposed between the excess-pressure pipe 16 and the air inlet opening 14, the pipe 16 may be tangentially connected with said can; and said can may be provided with dust-removing means, of the general character suggested in Figures 2 and 3. Aside from a dust-separating effect, the spiral movement imparted to the incoming air is favorable to its circulation.

In the figures last referred to, a cylindrical screen 29 is shown as disposed concentrically within the said can; and said can may be provided with additional dust-eliminating means such as a vertical slot 30, protected by a tangential lip 31,—the parts here referred to being merely illustrative of means optionally employed to prevent avoidable advance of dust through the inlet opening 14, or its equivalent.

In ordinary operation, it will be understood that whenever the starting of the engine occasions rotation of the fan 13 (or whenever bodily advance of a vehicle equipped in the described manner raises a sufficient blast of air by the action of funnel 25, or its equivalent) movements of air inward through the opening 14 and outward through any opening 15 assure an adequate ventilation of the crankcase element 11, or its equivalent,—this result being reliably obtained even at low engine speeds and without the employment of any relatively moving parts or any appreciable waste of power.

Although the foregoing description includes details of but a single embodiment of the present invention, it should be understood, not only that various features thereof may be independently used but also, that numerous modifications might easily be devised,—all within the scope of said invention, as the latter is indicated above and in the following claims.

60 I claim:

1. In a system of ventilation for a crankcase provided with a plurality of openings; a blast-receiving funnel; and means, connected with said funnel, for producing opposite pressure effects through the said open-

ings, to advance air through said crankcase.

2. A combination as defined in claim 1, in which a radiator-cooling fan is disposed partially in front of said funnel.

3. A combination as defined in claim 1, in which said pressure-producing means includes an aspirator organization, which is connected with a reduced-pressure pipe communicating with one of said openings, 75 and includes also an excess-pressure pipe which communicates with another of said openings.

4. A combination as defined in claim 1 in which said pressure-producing means includes an aspirator organization which is connected with a reduced-pressure pipe communicating with one of said openings, and includes also an excess-pressure pipe which communicates, by way of an air-conditioning breather can, with another of said openings.

5. In means for advancing air through a breather can opening into a crankcase of an engine which drives a cooling fan: a pipe communicating with said can; and means rendering rotation of said fan effective to advance air through said pipe and thence inwardly through said can, said last-mentioned means comprising a forwardly-facing funnel which is connected also with means for withdrawing air from said crankcase.

6. For use in a combination of the general character described: an element to be ventilated through openings provided therein, a blast-raising element provided with a plurality of blast-exit openings; and separate means, respectively interposed between said exit openings and the respective openings 105 which are provided in the element to be ventilated, rendering the resultant blast effective to produce opposite movements of air through said last-mentioned openings.

In testimony whereof I affix my signature. 110
GEORGE H. DAUBNER.
